UNITED STATES PATENT OFFICE.

GRAHAM D. TYSOR, OF SALEM, VIRGINIA, ASSIGNOR TO COMAS CIGARETTE MACHINE COMPANY, OF SALEM, VIRGINIA, A CORPORATION OF VIRGINIA.

CUTTING MECHANISM FOR CIGARETTE-MACHINES.

1,184,218.

Specification of Letters Patent.

Patented May 23, 1916.

Application filed January 18, 1915. Serial No. 2,884.

To all whom it may concern:

Be it known that I, GRAHAM D. TYSOR, of Salem, Virginia, have invented certain new and useful Improvements in Cutting Mechanism for Cigarette-Machines, of which the following is a specification.

This invention relates to improvements in the cutting mechanism for cigarette machines and the object of the invention is to 10 provide a machine of this character which will be durable and efficient in use and capable of withstanding the hard service to which mechanisms of this kind are subjected.

15 The invention, in its preferable embodiment, consists in the peculiar construction and arrangement of parts hereinafter described and then definitely claimed.

In the drawings accompanying and forming part hereof: Figure 1 is a side elevation of the end of a cigarette machine containing my improvements. Fig. 2 is a top plan view of the same. Fig. 3 is an end elevation. Fig. 4 is a sectional detail showing 25 the mounting for the rotary cutter. Fig. 5 is a perspective view of part of the gearing.

Referring now to the details of the drawings by numerals: 1 represents the main 30 frame or table having slides 2 and 3 thereon (see Fig. 3). The sliding frame 4 for carrying the cutter is mounted to move back and forth upon the slides 2 and 3 and to give such motion to the cutter frame and its cutter, I connect said frame to a crank pin 6 by means of a link 8, this crank pin being adjustably connected to a crank disk 10 shown in Figs. 1 and 2. This crank disk is supported upon a vertical shaft 12 and is given 35 rotary movement by gearing hereinafter described. It is sufficient to here state that the revolution of the crank disk 10 will cause the cutter frame 4 to be moved back and forth on the slides 2 and 3, each revolution of the crank disk moving the cutter frame once in each direction. The cutter frame 4 is provided with standards 14 and 40 16 in which is mounted a shaft 18 to which is secured a pulley 20 driven by means of a belt 22 from a pulley 24 secured to the drive shaft 26. Upon the shaft 18 is mounted a knife carrying arm 28 having a knife shaft 30 journaled in one end thereof, this shaft

having a pulley 32 and a rotary knife 34 secured thereon. The pulley 32 is connected 55 by means of a belt 36 with a second pulley 38 secured to the aforesaid shaft 18. This construction results in motion being transmitted from the shaft 26 to the shaft 18 and from said shaft 18 through the belt 36 to 60 the shaft 30 whereby the cutter 34 is continuously rotated. Therefore when the knife carrying arm 28 is in the position shown in Fig. 3, the cutter 34 will be in the act of cutting the cigarette. After the cigarette is 65 completely cut, it is necessary for the knife carrying arm 28 to be raised to move the rotary cutter 34 away from the cigarette. To accomplish this purpose the rear end of the knife carrying arm 28 is formed as will now 70 be described. A second arm 40 is formed integrally with the knife carrying arm 28 and extends on the other side of the shaft 18. A third arm 42 is journaled upon the shaft 18 and the two arms 40 and 42 are connected 75 together by a spring 44 so that in case of necessity one of these arms may move with respect to the other. The arm 42 is connected by means of a turn buckle arrangement 46 with a crank pin 48 driven in a manner 80 to be described and as shown in Figs. 3 and 4. It follows from the construction above described that when the crank pin 48 moves downward, as seen in Fig. 3, the levers 40 and 42 will be likewise drawn downward so 85 as to move the knife carrying arm 28 upward and thereby move the rotary cutter in the same direction and away from the cigarette rod. However, during the other half 90 of the movement of the crank pin 48 the turn buckle is forced upward, thereby moving the levers 40 and 42 upward and at the same time causing the rotary cutter 34 to move downward to again cut the cigarette rod. The object of the two sets of arms 40 95 and 42 and the spring 44 is to prevent damage to the rotary cutter. For example, if there should be a small piece of wire in the cigarette rod or should any other obstruction be in the path of the knife, the upward 100 movement of the turn buckle 46 would move the arm 42 upward and the spring 44 would also move the arm 40 with the arm 42 until the wire or other obstruction causes sufficient resistance to the downward movement 105 of the knife 34 to permit the spring 44 to

give, the result being that further upward movement of the turn buckle 46 will move the arm 42 only, the spring 44 stretching and not moving the arm 40 to the limit of its movement. Thus, the rotary knife would not be forced to cut through a wire or any similar obstruction.

I will now describe the gearing for moving the crank pin 48 and the crank disk 10 to give simultaneous movement to the knife carriage and to the rotary knife. The drive shaft 26, hereinbefore referred to, is provided with a pulley 50 connected by a belt 52 with a pulley 54 on a main shaft 56. This main shaft 56 drives the entire gearing for moving the knife downwardly at the same time that the knife frame is moved back and forth. To this end the main shaft 56 is provided with a worm 58 which meshes with and drives a worm gear 60 secured to a shaft 62. To this shaft 62 is connected a gear 64 which meshes with an idler gear 65 and drives a gear 66 on the counter shaft 68. To the shaft 68 is also secured a gear 70 which rotates in the direction of the arrow shown in Fig. 5 and this gear drives a gear 72 through an idler 74 shown in full lines in Fig. 5. The gear 72 is loose upon the shaft 62 and has fixedly secured to it a worm 76 which meshes with and drives a worm gear 78 secured to the aforesaid shaft 12 which gives movement to the crank disk 10 before described as giving back and forth movement to the knife carriage 4. It follows from this construction that motion is transmitted from the drive shaft 26 to the main shaft 56 and from this shaft 56 to the gearing just described to the crank disk 10 and that as said crank disk 10 is rotated, the knife carriage is moved back and forth upon its slides 2 and 3. The main frame of the machine also supports a standard 80 in which is journaled a shaft 82 carrying the crank pin 48 hereinbefore described for giving downward movement to the rotary cutter 34. This shaft 82 has connected to it a disk 84 which is driven from the gear 66 hereinbefore described. It will be obvious that any connection between said gear 66 and said disk 84 will cause the turn buckle 46 to have an up and down movement for each revolution of said gear 66, disk 84 and crank pin 48. However, I do not desire to have a rigid connection between the gear 66 and disk 84 for I deem it important that the cutter shall be given a quick dip down against the cigarette rod for the purpose of cutting said rod and to slowly move during the rest of its period of movement. To accomplish this purpose I journal the shaft 82 eccentrically with respect to shaft 68 and connect the gear 66 with the disk 84 by means of a link 90 shown in Figs. 1 and 3. This eccentric relation of the two shafts, and the link ar-

angement for driving the disk 84 from the gear 66 results in a quick dipping movement of the cutter 34 at one period of movement and a relatively slow movement during the balance of the rotation.

The operation of my machine has been described so fully in the description of the details that any further reference to the operation is not necessary.

It is obvious that modifications and changes may be made in the construction and arrangement of my invention without departing from the spirit thereof, the scope of which is set forth in the appended claims.

What I claim as my invention is:

1. In a cigarette machine, the combination of a cutter shaft, a support therefor formed in two parts one of which moves with the cutter shaft, and a spring connection between said parts whereby one of said parts may be moved in one direction without moving the cutter and the other, substantially as described.

2. In a cigarette machine, the combination of a cutter shaft, an arm for supporting said shaft and permitting it to be moved up and down, a second arm co-acting with the first arm, and a spring connection between said arms, said arms normally moving together but having independent movement when the cutter strikes an obstacle, substantially as described.

3. In a cigarette machine, the combination of a traveling cutter, means for moving said cutter against the cigarette to cut the same, said means comprising two shafts eccentrically arranged, a disk or gear on each shaft, and a link pivotally connected to each of said last mentioned parts whereby a quick movement is given to the cutter during one period of its stroke, substantially as described.

4. In a cigarette machine, the combination of a traveling cutter, means for moving said cutter against the cigarette, said means comprising two shafts eccentrically arranged, a disk or gear on each shaft, a link pivotally connected with each of said disks or gears, and a crank pin connecting one of said shafts with the traveling cutter, substantially as described.

5. In a cigarette machine, the combination of a traveling cutter, a frame carrying said cutter and adapted to be moved up and down, means for moving said frame up and down comprising two shafts eccentrically arranged with respect to each other, a crank pin connecting one of said shafts with the aforesaid cutter frame, and a link pivotally connecting the eccentrically arranged shafts, whereby a quick movement is given to the cutter during one period of its stroke, substantially as described.

6. In a cigarette machine, the combination of a traveling cutter, a frame carrying said

cutter and adapted to be moved up and down, means for moving said frame up and down comprising two shafts eccentrically arranged with respect to each other, a crank 5 pin connecting one of said shafts with the aforesaid cutter frame, a disk or gear for each of said shafts, and a link pivotally connecting said disks or gears, whereby a quick movement is given to the cutter during one period of its stroke, substantially as described.

7. In a cigarette machine, the combination of a cutter carriage, a rotary cutter carried thereby, means for moving said carriage and cutter in line with the movement of the cigarette rod, means for moving said cutter up and down against the cigarette rod to cut the same, said means comprising two shafts eccentrically arranged with respect to 15 each other, and a link pivotally connecting said shafts whereby a quick movement is 20

given to the cutter during one period of its stroke, substantially as described.

8. In a cigarette machine, the combination of a cutter carriage, a rotary cutter carried thereby, means for moving said carriage and cutter in line with the movement of the cigarette rod, means for moving said cutter up and down against the cigarette rod to cut the same, said means comprising two 25 shafts eccentrically arranged with respect to each other, a disk or gear for each of said shafts, and a link pivotally connecting said disks or gears whereby a quick movement is given to the cutter during one 30 period of its stroke, substantially as described.

In testimony whereof I affix my signature in presence of two witnesses.

GRAHAM D. TYSOR.
